E. C. FULLER COMPANY, OF NEW YORK, N. Y., A CORPORATION OF
NEW YORK.

FRONT REGISTER FOR SHEET-FOLDING AND OTHER MACHINES.

No. 824,755.

Specification of Letters Patent.

Patented July 3, 1906.

Application filed January 28, 1905. Serial No. 243,102.

To all whom it may concern:

Be it known that I, CHARLES A. STURTEVANT, a citizen of the United States, residing at Plainfield, in the county of Union and State 5 of New Jersey, have invented new and useful Improvements in Front Registers for Sheet-Folding and other Machines, of which the following is a specification.

This invention relates to front gages or 10 registers for use in registering sheets at the front edge before being fed to a folding, printing, ruling, or other machine which operates on the sheets.

The object of this invention is to produce a 15 register for this purpose which is preferably rigid while the sheet is being fed against the same, thereby insuring a correct register of the sheet.

My invention has the further object to provide 20 a front register which is simple in construction, reliable in operation, and which contains no parts which are delicate and liable to get out of order.

In the accompanying drawings, consisting 25 of two sheets, Figure 1 is a fragmentary top plan view of a folding-machine equipped with my improved front registering mechanism. Fig. 2 is a fragmentary vertical longitudinal section of the same on an enlarged scale. Fig. 3 is a fragmentary top plan view 30 of one end of the same, on an enlarged scale and showing some parts adjusted to a different position. Fig. 4 is a vertical cross-section in line 4-4, Fig. 2. Fig. 5 is a fragmentary cross-section in line 5-5, Fig. 3.

Similar letters of reference indicate corresponding parts throughout the several views.

The folding-machine and its sheet-carrying mechanism shown in the drawings for 40 illustrating the application of my improved front register consists, essentially, of a frame A; a horizontal tape or receiving roller B, journaled at opposite ends in bearings formed in brackets C on the frame; sheet-carrying 45 tapes b, passing around the receiving-roller; drop-rollers D, arranged above the tape-roller and movable toward and from the same; a transverse roller-shaft d, carrying the drop-rollers; rock-arms e, carrying the 50 drop-roller shaft at their front ends; a transverse rock-shaft E, journaled in bearings on the brackets C and carrying said rock-arms at their rear ends; a table A', from which the

sheets are fed by the operator to the tapes and rollers; a pair of folding-rollers B', arranged in rear of the receiving and drop rollers, and a folding-blade B² for carrying the sheets from the tapes between the folding-rollers. While the drop-rollers are elevated the operator feeds the sheet with its 55 front edge between the tape-roller and the drop-rollers, and after this has been done the drop-rollers descend upon the sheet and cause the same to be fed forward by the tapes to the devices which subsequently operate upon the same in a well-known manner.

My improved front-registering mechanism which coöperates with the above-described sheet-carrying mechanism is constructed as follows:

F represents one or more front gages which are adapted to move downwardly and forwardly across the path of the sheets adjacent to the tape-roller for intercepting and gaging the sheet, as shown by full lines in 75 Fig. 2, and to move upwardly and backwardly for clearing the path of the sheet and permitting the same to be carried away by the tapes, as shown by dotted lines in the same figure. Each of these gages is pivoted 80 at its upper end by a horizontal cross-pin g to the front end of a bracket G, which is secured to the main frame and is provided above its pivot with a short lug or arm f.

H is a shifting rod which is pivotally connected at its front end with the gage-arm f by a horizontal pin h, projecting laterally from the front end of the same through an opening in said arm. Near its rear end the shifting rod passes through a downwardly-opening 85 recess i, formed in a guide-lug I on one side of the bracket G. This rod is confined in said recess by a transverse pin i', which connects the parts of said lug below the shifting rod and closes the mouth of said recess. The 90 shifting rod is moved forwardly by a spring J, surrounding the rod and bearing at opposite ends against the guide-lug I and a shoulder or pin j on the rod. At its rear end the shifting rod is provided with a shoulder or 95 finger k, which projects downwardly in rear of a tappet K. This tappet oscillates in unison with the rise and fall of the drop-rollers and is preferably constructed in the form of a web or plate, which is arranged in a longitudinal groove k' in the upper side of the 100 105

rock-shaft E. The tappet-plate is preferably secured in said groove by means of reduced portions or keys l, formed at opposite ends of the tappet-plate and engaging with 5 the bore of the openings in the sleeves or hubs of the rock-arms e, which receive the rock-shaft and fit around said keys, as shown in Fig. 5.

When the rock-shaft turns in the direction 10 for lifting the drop-rollers from the tape-roller, the tappet moves backwardly and carries the shifting rod in the same direction by engaging the finger at its rear end, thereby causing the gage to be turned from its inoperative 15 or elevated position (shown by dotted lines in Fig. 2) to its operative or lowered position. (Shown in full lines in said figure.) While in this position the gages are perfectly rigid against backward movement, being 20 thus held by the tappet, which positively moves the shifting rod backwardly, thereby preventing displacement of the front gages upon being engaged by the sheets and insuring correct register of the same at their front 25 edges.

As the drop-rollers descend upon the sheet the plate is moved forwardly by the movement of the rock-shaft in that direction. This permits the springs J to also move the 30 shifting rods forwardly and cause the gages to be moved from their lowered operative position (shown in full lines in Fig. 2) to their elevated inoperative position, (shown in dotted lines in the same figure,) thereby clearing the 35 path of the sheet and permitting the same to be carried away by the propelling mechanism.

When it is desired to adjust the gages transversely of the path of the sheets for 40 adapting them to sheets of different width, it is only necessary to shift the brackets G in that direction on the frame. This is rendered possible by constructing the rear part of each gage-bracket G in the form of a jaw 45 g', which embraces a cross-bar g² of the frame and is movably secured thereto by a clamping-screw g³. While thus adjusting the gage-brackets the fingers of the shifting rods move along the rear side of the tappet-plate 50 and always remain in operative relation thereto, thus avoiding the necessity of readjustment of the gage mechanism when shifting the same for adapting the mechanism to different sizes of sheets.

55 I claim as my invention—

1. A front register for sheet-folding and other machines comprising a receiving-roller, a drop-roller arranged above the receiving-roller, a rock-shaft arranged adjacent to the 60 drop-roller, a vertically-swinging gage arranged above the receiving-roller, a spring operating to move said gage out of the path of the sheets, a shifting rod connected with said gage, and a tappet arranged on said rock-shaft and operating to shift said rod in 65

the direction for moving the gage into the path of the sheets, substantially as set forth.

2. A front register for sheet-folding and other machines comprising a vertically-swinging gage having an arm above its pivot, 70 a shifting rod connected at one end with said arm and provided at its opposite end with a finger or shoulder, a spring operating to move said gage out of the path of the sheets and a rocking tappet arranged to engage said finger 75 or shoulder and move the gage into the path of the sheets, substantially as set forth.

3. A front register for sheet-folding and other machines comprising a vertically-swinging gage having an arm above its pivot, 80 a shifting rod connected at one end with said arm and provided at its opposite end with a finger or shoulder, a rocking tappet arranged to engage said finger or shoulder and move said gage into the path of the sheets, and a 85 spring operating to move the gage out of the path of the sheets, substantially as set forth.

4. A front register for sheet-folding and other machines comprising a vertically-swinging gage having an arm above its pivot, 90 a shifting rod connected at one end with said arm and provided at its opposite end with a shoulder or finger, a rock-shaft provided with a tappet engaging with said shoulder, or finger and operating to move the gage into the 95 path of the sheets, and a spring engaging with a shoulder on said rod and operating to move said gage out of the path of the sheets, substantially as set forth.

5. A front register for sheet-folding and 100 other machines, comprising a bracket, a gage pivoted on said bracket and having an arm above its pivot, a shifting rod connected at one end with said arm, a guide on the bracket 105 for said rod, a spring operating to move said gage out of the path of the sheets and a rocking tappet arranged to engage a shoulder on said rod and move the gage into the path of the sheets, substantially as set forth.

6. A front register for sheet-folding and 110 other machines, comprising a bracket, a gage pivoted on said bracket and having an arm above its pivot, a shifting rod connected at one end with said arm, a guide for said rod arranged on the bracket, a spring surrounding 115 said rod between a shoulder thereon and said guide and operating to move said gage out of the path of said sheets, and a rocking tappet engaging with a shoulder on said rod and operating to move said gage into the 120 path of the sheets, substantially as set forth.

7. A front register for sheet-folding and other machines, comprising a bracket, a gage pivoted on said bracket and having an arm above its pivot, a shifting rod connected at 125 one end with said arm, a guide-lug on said bracket having a downwardly-opening recess which receives said rod, a pin arranged on said lug and closing the mouth of said recess below said rod, a spring operating to move 130

the gage out of the path of the sheets, and a 5
rocking tappet engaging with a shoulder on
the shifting rod and operating to move the
gage into the path of the sheets, substantially
as set forth.

8. A front register for sheet-folding and
other machines, comprising a rock-shaft ar- 10
ranged transversely of the path of the sheets,
a bracket adjustable transversely of said
path, a gage pivoted on said bracket, a spring
for moving said gage out of the path of the
sheets, and means for moving the gage into 15
the path of the sheets comprising a shifting
rod connected with said gage, and a tappet-
plate arranged lengthwise of the rock-shaft
and engaging with a shoulder on said shifting
rod for moving the gage into the path of the 20
sheets, substantially as set forth.

9. A front register for sheet-folding and
other machines, comprising a rock-shaft ar- 25
ranged transversely of the path of the sheets,
a bracket adjustable transversely of said
path, a gage pivoted on said bracket, a spring
for moving said gage out of the path of the
sheets and means for moving the gage into 30
the path of the sheets comprising a shifting
rod connected with said gage, a tappet-plate
arranged in a longitudinal groove in said
shaft and engaging with a shoulder on said
rod for moving the gage into the path of the 35
sheets, keys arranged at the ends of said
plate, and sleeves arranged on said shaft and
fitting over said keys, substantially as set
forth.

35 10. The combination of a sheet-propelling

device comprising a tape-roller, a drop-roller
movable toward and from the tape-roller, a 40
roller-shaft supporting the drop-roller, a rock-
shaft provided with rock-arms in which the
roller-shaft is journaled, and a front register 45
comprising a vertically-swinging gage ar-
ranged above the tape-roller, a shifting rod
connected with said gage, a spring operating
on said rod to turn the gage out of the path of
the sheets, and a tappet arranged on said 50
rock-shaft and operatively engaging said rod
for turning the gage into the path of the
sheets, substantially as set forth.

11. The combination of a sheet-propelling
device comprising a tape-roller, carrying- 55
tapes passing around said roller, drop-rollers
movable toward and from the tape-roller, a
roller-shaft supporting said drop-rollers, a
rock-shaft, rock-arms connected with said
rock-shaft and supporting said roller-shaft, 60
and a front register comprising a gage mov-
able into and out of the path of the sheets, a
shifting rod connected with the gage, a tap-
pet on said rock-shaft engaging with a shoul-
der on said rod for moving the gage in one di- 65
rection, and a spring for moving the gage in
the opposite direction, substantially as set
forth.

Witness my hand this 25th day of January,
1905.
